UNITED STATES PATENT OFFICE.

CALLIX LACOSSE, OF BAY CITY, MICHIGAN.

MEAT-TENDERER.

SPECIFICATION forming part of Letters Patent No. 326,660, dated September 22, 1885.

Application filed May 18, 1885. (No model.)

To all whom it may concern:

Be it known that I, CALLIX LACOSSE, a citizen of the United States, residing at Bay City, in the county of Bay and State of Michigan, have invented certain new and useful Improvements in Meat-Tenderers, of which the following is a full, clear, and exact description.

My invention relates to that class of meat-tenderers used as a pounder for tendering the meat; and it consists in the arrangement and combination of the different parts, as I hereinafter more fully describe and claim.

The object of my invention is to produce a device for tendering the meat and a means of cutting or sawing small bones in the meat with one tool, and I accomplish this object by means of the device illustrated in the accompanying drawings, in which—

Figure 1 is a side view of my improved tenderer with the saw and knife closed. Fig. 2 is a view of the same with the knife open and saw closed. Fig. 3 is a view of the same with the saw open and knife closed. Fig. 4 is a section at x x in Fig. 1.

Similar letters refer to similar parts throughout the several views.

a represents a hammer-like meat-tenderer, having on its pounding-face the teeth b , and passing through its body the handle c . Secured into the extended end of the handle c is the ring d , with which the tool may be hung up. A portion, p , of the body a opposite the face thereof is extended beyond the handle c , and provided with the slot n , into which is placed the saw f and knife e , and secured therein by the pivot i in such a manner that

they may be extended, as in Figs. 2 and 3, or closed against the handle c , as shown in Fig. 1, and are held in either position by the thumb-screws h , passed through either side of the extended portion p , and extending a short distance into the side of the pivoted portion of the saw or knife blades, a small recess being provided in those parts for that purpose, as shown in Fig. 4, and a second recess is made in the said parts in a suitable position, so that when the saw or knife shall be open it is held in that position by turning up the set-screw h with a like result, when either or both may be closed.

The knife is useful for cutting and trimming meat and removing the bones therefrom, and can be used for chopping the tough and hard parts, as the weight of the tenderer a adds to the force of the blow, and the saw may be operated for sawing the bones, when cutting up small animals, &c., to great advantage in preparing them for cooking.

What I claim as my invention, and desire to secure by Letters Patent, is—

In a meat-tenderer, the combination of the body a , having the handle c , and the teeth b on its pounding-face, and the extended portion p , provided with the slot n , with the saw-blade f and knife-blade e , pivoted in the said slot n , and held in an open or closed position by the set-screw h , substantially as and for the purpose specified.

CALLIX LACOSSE.
